INVENTOR
Charles Ray Savery
BY
C. E. Beach
ATTORNEY

UNITED STATES PATENT OFFICE.

CHARLES RAY SAVERY, OF BINGHAMTON, NEW YORK.

ATTACHMENT FOR TEMPERATURE-OBSERVING DEVICES.

Application filed January 5, 1924. Serial No. 684,675.

This invention relates to illuminating attachments for temperature observing devices, and is particularly suited for use in connection with radiator thermometer devices employed upon the radiator caps of automobiles.

Various arrangements have heretofore been devised for providing illumination for temperature observing devices, but all of said prior art arrangements which are suited in connection with automobile radiator thermometer devices are either of a character necessitating that they be built into the device during the process of original manufacture or such as to constitute an extraneous attachment objectionable both from considerations of appearance and utility. Inasmuch as there are said to be hundreds of thousands of devices of this character now in use which are not provided with any means for the illumination thereof when needed, the owners of such devices are desirous of obtaining attachments therefor such as will enable them to enjoy the advantages of an illuminated device during night driving without either necessity of discarding their present devices or of applying thereto an attachment which will render same offensively objectionable in appearance or impair the facility with which they may utilize the radiator caps to which these devices are applied.

It is an important object of this invention to provide an attachment of the character described which can be readily applied to temperature observing devices already in use.

A further object is to provide such an attachment which is suited for rapid and inexpensive manufacture, which will not impair the appearance of the thermometer device to which it is applied, which is simple and durable, which can be quickly applied by an ordinary mechanic without the use of any special tools or appliances and without cutting, bending or otherwise re-forming any part of the thermometer device, and which is not so formed as to particularly invite lodgment thereon of dust, mud, snow or ice, especially in such manner as to impair the effectiveness thereof.

Still further objects will be in part obvious and in part more specifically stated in the description of this invention hereinafter set forth.

With the aforesaid objects in view, this invention consists of the novel features of

structure and arrangement of parts pointed out in the subjoined claims and hereinafter described with relation to a specific embodiment thereof illustrated in the annexed drawing, wherein like parts are designated by similar reference characters, and in which

Figure 1 is a side elevation, partly in section, of an attachment embodying this invention together with a thermometer device for use with which said attachment is suited, and

Fig. 2 is a face view of the attachment and device of Fig. 1.

In order to facilitate comprehension of this invention, and for convenience of illustration, an embodiment thereof is shown by the accompanying drawing in connection with a well-known form of temperature observing device comprising the annular frame 21, the pedestal 22 upon which said frame is mounted, the thermometer tube 23 contained within said frame and pedestal, the dial plate 24 mounted within said frame at one side of said thermometer, the bezel 25 carrying the crystal 26 and secured to a side of the frame 21 (at the other side of said thermometer) by screws 27, the bezel 25' carrying the crystal 26' which, in the absence of the attachment of this invention, is secured to the other side of said frame by screws similar to the screws 27, and the supplemental dial plate 24' which is, under like conditions, clamped between the bezel 25' and the dial plate 24.

The temperature observing device thus far described is shown as having an illuminating attachment associated therewith, which attachment is illustrative of this invention and comprises the annular member 31 and the receptacle 32 for the lamp 33.

Said member 31 has a peripheral contour harmonizing with those of the frame 21 and the bezel 25', and the opposite faces of said member are so formed as to be suited for interposition between said frame and bezel, to make snug joints therewith. Said member is so formed as to provide for passage therethrough of the attaching screws 27' which serve to hold both this attachment and said bezel in intended relationship with the frame 21; the central opening through said member being of such size and form as to provide space for mounting therein the receptacle 32 and lamp 33, and so as to provide for the passage of light from said lamp

through suitable openings in the dial plate 24 to the tube of the thermometer 23. It is deemed preferable to provide a slot 28 in the dial plate 24 extending downwardly from the opening 29 regularly provided in such plate, said slot being so positioned as to provide for the illumination of the tube of the thermometer 23 for a suitable distance below the opening 29. It is also believed to be desirable to provide a covering of translucent material, as indicated at 30, for the slot 28 and opening 29, so as to prevent direct glare from the lamp 33 from reaching the eyes of the driver of a vehicle upon which the device and attachment shown have been mounted; it may also be desirable that the covering of the opening 29 shall be of a color distinctive from that of the covering of the slot 28.

20 The terminal 34 communicates with the receptacle 32, and said terminal passes through the side wall of the member 31 and projects from the periphery thereof so as to facilitate the supply of energy to the lamp 33 from a conductor, such, for example, as the conventionally indicated conductor 35, which conductor may be provided with a spring contact such as that indicated at 36 for readily detachable connection with said terminal 34.

In order to prevent escape of glaring rays from the lamp 33 through the opening 29' provided in the supplemental dial plate 24', a translucent screen 37 is so applied as to cover said opening; said screen being of such a character as will permit sufficient light to enter through the opening 29' during the day time (when the lamp 33 is not burning) as will suitably assist the observer in ascertaining the position of the indicating fluid in the tube of the thermometer 23.

In applying the attachment of this invention to a device such as that shown, the screws which originally held the bezel 25' in place are first removed, this bezel taken off and the supplemental dial plate 24' also removed; then, if same is not already therein provided, the slot 28 may be cut in the dial plate 24 and, if it is desired to use such shields, the covering 30 may be applied to the dial plate 24 and the translucent screen 37 correspondingly applied to the supplemental dial plate 24'. A suitable lamp 33 should then be placed in the receptacle 32, and the member 31 should be placed in intended relation with the frame 21 so that the openings provided for the attaching screws through said member will register with the threaded openings provided in said frame. 60 The supplemental dial plate 24' and the bezel 25' should then be applied to the outer face of the member 31, and secured in position by the screws 27'.

It will be understood by those skilled in this art that the member 31 may be of such

diameter that the screws 27' may pass through the principal opening through said member or outside of the periphery thereof, in either of which events it would be unnecessary to provide openings through said member for such screws; it will also be readily understood that the member 31 and bezel 25' may be secured to the frame 21 other than by the screws 27' as shown; and that various other modifications of structure and arrangement may be made without departing from the spirit of this invention.

What I therefore claim and desire to secure by Letters Patent of the United States of America is:

1. An attachment for a temperature observing device having a frame of annular configuration with threaded openings therein for receiving attaching screws of a cover for one side of said frame, and the cover having openings positioned for registry with the threaded openings in said frame—said attachment comprising an annular member suited for interposition between the frame and cover of such a device, said member having openings therethrough so positioned that, when said member is interposed between the frame and cover of such a device, said openings therethrough will register with and form channels of communication between the threaded openings in such frame and the corresponding openings in said cover, and a receptacle for lighting means supported and contained within said member.

2. An attachment for a temperature observing device having a frame of annular configuration with threaded openings therein for receiving attaching screws of a cover for one side of said frame, and the cover having openings positioned for registry with the threaded openings in said frame,—said attachment comprising an annular member suited for interposition between the frame and cover of such a device, said member so formed as to provide for the passage of cover attaching screws therethrough, and a receptacle for lighting means supported and contained within said member.

3. An attachment for a temperature observing device having a frame with threaded openings therein for receiving attaching screws of a cover for one side of said frame, and the cover having openings positioned for registry with the threaded openings in said frame,—said attachment comprising a member so formed that, when interposed in the intended manner between the frame and cover of such a device, passageway will be provided for cover attaching screws, and a receptacle for lighting means supported and contained within said member.

4. An attachment for a temperature observing device having a frame of annular configuration, a cover adapted to close one

side of said frame, and means for attaching said cover to said frame,—said attachment comprising an annular member suited for interposition between the frame and cover of such a device, and lighting means supported and contained within said member between said frame and said cover.

5. An attachment for a temperature observing device having a casing with a removable wall section,—said attachment comprising an extension member for said casing, said member having an opening therethrough for a suitable lamp and having a peripheral contour harmonizing with those of such casing and its removable wall section and being formed and arranged for interpositioning therebetween to thereby separate said movable wall section a sufficient distance from said casing to provide space for such 10 a lamp, a receptacle within said opening positioned for therein supporting such a lamp, and a terminal for the supply of energy to

said receptacle, said terminal extending through the wall of said member.

6. An attachment for a temperature observing device having a casing one of the walls of which is transparent and another of the walls of which is removably secured to said casing,—said attachment comprising an extension member for said casing, said member having an opening therethrough for a suitable lamp and having a peripheral contour harmonizing with those of such casing and its removable wall and being formed and arranged for interpositioning therebetween to thereby separate said movable wall section a sufficient distance from said casing to provide space for such a lamp, and a receptacle within said opening positioned for therein supporting such a lamp. 25 30 35 40

In witness whereof, I hereunto subscribe my name, this 3rd day of January, 1924.

CHAS. RAY SAVERY.
